Alvin M. Miller

ATTORNEY

UNITED STATES PATENT OFFICE.

MORTON A. OPPENHEIMER, OF PHILADELPHIA, PENNSYLVANIA.

HAIR NET.

Application filed July 10, 1924. Serial No. 725,235.

To all whom it may concern:

Be it known that I, MORTON A. OPPENHEIMER, a citizen of the United States, residing at Philadelphia, in the county of 5 Philadelphia and State of Pennsylvania, have invented certain new and useful Improvements in Hair Nets, of which the following is a specification.

The invention relates to hair nets designed to neatly confine the hair of the wearers thereof and has for its object to provide a net of that character which is peculiarly constructed to adapt the same to effective use without the need of securing 10 means such as hairpins and the like, and particularly over "bobbed" hair of the various styles now popular.

With the above and other objects in view that will hereinafter appear the invention 15 further resides in the novel details of construction fully described in the following detailed description, particularly pointed out in the appended claim and illustrated in the accompanying drawing, in which:—

20 The figure illustrates, in side elevation, a head, the hair of which is of one of the "bobbed" styles and confined in a net constructed in accordance with the invention.

In carrying out the invention the strands 25 of the net are woven tied or connected, single or double, into meshes forming a fabric body 1 of a substantial skull cap shape of the general contour of the head for more or less closely confining the hair thereof.

30 The edges of the cap are close-mesh formed to restrict the opening into the cap body to effect a holding-on of the net without the aid of hairpins or other securing means.

35 In the illustration of the drawing the edge of the net extending around the front from ear to ear approximately is close-meshed as at 2 to sort of cup that portion of the net to serve as a medium for holding the net to 40 position. The exact shape of this close-mesh portion may, of course, be varied to suit requirements of style. These close meshes are considerably less in size than those of the main body portion to provide 45 the contraction desired.

50 That edge of the net which is adapted to extend around the back of the head from ear to ear approximately, is closer-meshed as at 3 to cup the net down around the curve

presented by reason of the more or less close cropping of the hair at this point as indicated in the drawing. The close-mesh here referred to is much smaller than that of the body proper and is only a fraction as large as the close-meshed edge 2.

55 The structure here described and illustrated in the drawing provides a hair net which is adapted to neatly and effectively confine hair of the various "bobbed" styles and one which will snugly fit over the hair and be held to the desired position solely 60 because of its structural features and without the need of hairpins or other securing devices.

65 The net here disclosed supplies a crying need as the nets now marketed are not suited to use on bobbed hair and can only be used thereon, or even on coiffures of the pre-bobbed hair era, by the use of hairpins to position and secure them. Their use therefore, especially on bobbed hair, is troublesome and undesirable. It should also be obvious that the use of such nets as are now 70 commonly marketed do not present as neat an appearance as the net herein disclosed.

75 From the foregoing description, taken in connection with the accompanying drawings, the novel details of construction, manner of use, and advantages of the invention 80 will be apparent.

85 What I claim is:

90 A hair net having a body formed of open meshes to conform to the general contour of the human head, and a close-meshed edge portion adapted to extend around the back of the head following the style of the hair and restricting the lower back portion of the body to cup-fit the hair closely at that point, and a close-meshed edge portion adapted to 95 extend around the front of the head following the style of the hair and restricting the adjacent portions of the body to thus coat with the back close-meshed edge in preventing displacement of the net, the said front close-meshed edge extending approximately 100 from ear to ear around the front and the said back close-meshed edge extending approximately from ear to ear around the back and being of a mesh considerably 105 smaller than that of the front close-meshed edge.

MORTON A. OPPENHEIMER.
